[57] CLAIM

The ornamental design for an electroauricular therapy probe, as shown and described.

DESCRIPTION

FIG. 1 is a side elevation of an electroauricular therapy probe showing my new design;

FIG. 2 is a bottom plan view thereof;

FIG. 3 is a top plan view thereof;

FIG. 4 is an enlarged, fragmentary view of the upper end of the probe taken in the direction of the arrows 4—4 of FIG. 1;

FIG. 5 is a view similar to FIG. 4 but taken in the direction of the arrows 5—5 of FIG. 1;

FIG. 6 is a view similar to FIG. 4, but taken in the direction of the arrows 6—6 of FIG. 4; and

FIG. 7 is a view similar to FIG. 4, but taken in the direction of the arrows 7—7 of FIG. 4.
